FUSED ELECTRICAL CONNECTOR

John F. Conrad, Ebensburg, Pa., assignor to
Deltron Electric Products, Inc., Ebensburg, Pa.,
a corporation of Pennsylvania

Application February 10, 1953, Serial No. 336,115

8 Claims. (Cl. 200—132)

1

This invention relates to fused electrical connectors that are particularly suitable for use as taps for trolley wires or the like, and constitutes a modification of the connector disclosed in my application Serial No. 211,785, filed February 19, 1951, now Patent 2,636,957, dated April 28, 1953.

One object of my invention is to provide an improved manner of connecting the fuse links of a cartridge-type fuse to terminal members that are carried in a casing which contains the cartridge, the terminal members being, in turn, adapted for connection to the usual electrical conductors.

Another object of my invention is to provide an improved arrangement of fuse links and conductor members, whereby the parts and material contained within the cartridge shell can more conveniently be placed therein.

Still another object of my invention is to provide an improved manner of venting exhaust gases from the fuse cartridge.

A further object of my invention is to insure more dependable conductivity as between the fuse links and the terminal members of the casing.

In the accompanying drawing,

Figure 1 is a longitudinal sectional view through a connector that embodies my improved fuse structure;

Fig. 2 is a view showing the fuse links with conductor strips connected to the ends thereof, and

Fig. 3 is a view of one of the cartridge bushings of Fig. 1 detached from the holder.

A casing or holder 8 is of insulating material such as fibrous reinforced resin and has an insulating closure disc 9 pressed into one end thereof through which a sheathed cable 10 extends. A knurled block 11 of aluminum or other metal has tight fit in the casing 8, and the bared wires of the cable are clamped in a terminal block 12, by a set screw 13. The disc 9 and the block 11 have vent holes.

A coupling member 14 that serves as a terminal block for the fuse cartridge has threaded engagement with the member 12 and has a recess for the reception of a tubular clamping member 15 through which the wires 16 of the cable 10 extend and are flared or fanned out at their inner ends 17, so that they will be clamped against a shoulder 18 in the coupling member 14, when the coupling member and the member 12 are screwed tightly together. The coupling member has vent holes 19 through

which gases may escape upon rupture of the fuse, as hereinafter explained.

A cartridge shell 21 has bushings 22 and 23 in its ends, that are knurled on their peripheries, for tight fit with the shell 21. These bushings are centrally perforated as shown at 26 and 27 for the escape of gases from the cartridge. The bushing 22 is similar in shape to the bushing 23 of Fig. 3 and has screw-threaded engagement with the coupling 14, and the passageway 26 has communication with the vent holes 19.

The bushing 22 has a tubular nipple-like extension at 28 for supporting the ends of a group of conductor leaves 29, the leaves having holes 30 through which the nipple 28 extends and the nipple being peened down to hold the leaves in place.

The leaves 29 are connected to fuse links 31 by a rivet 32. At their other ends, the fuse links are connected by a rivet 33 to the ends of the conductor leaves 34 whose ends extend between the fuse links and are perforated to receive the rivet 33. At their mid portions, the leaves are bent and have holes through which a tubular extension 35 of the bushing 23 projects, the end of the extension being peened down to hold the leaves in place.

At its upper end, the casing 8 has a bushing 39 firmly secured therein as by knurling the bushing and making a press fit. A terminal block 40 has threaded engagement with the bushing 39 and an escape vent 41 for gases.

The bushing 23 has threaded engagement with the terminal block 40 and gases caused through rupture of the fuse links will escape from the shell, through the passageways or vent 27 and 41. The block 40 is threaded for the reception of a trolley-wire engaging hook 42 or some other suitable connecting device. The outer end of the block 40 is flanged over at 43 to hold a rubber disc 44 in place for engagement with the end of the casing 8.

The fuse leaves 29 are made of extra length as shown in the drawing, to facilitate assembling of the device, since the plug 22 can be connected to the leaves while it is withdrawn from the shell 21, and the shell then filled with an inert powder. The plug can then be inserted into the end of shell and the shell pressed around it. The leaves 29 are bendable or collapsible to permit this removal and insertion of the plug.

Upon rupture of the fuse, gases will exit through the ports 26—19 and 27—41. To prevent accidental sifting out of the powder, gauze-like discs 45 will be placed over the inner ends

of the vents 26 and 27. These discs will be ruptured upon explosion within the cartridge, the gases will then be vented from the shell 21 and the casing 8.

In order to replace a fuse, the terminal block 40 will be unscrewed from the bushing 39 and the casing 8 and the cable 10 slid longitudinally with respect to one another to fully expose the cartridge shell and the terminal block 14. It is a simple procedure to then unscrew the cartridge bushings 22-23 from the terminal blocks 14 and 40.

I claim as my invention:

1. An electrical connector comprising a pair of electrically-conductive terminal blocks, a tubular holder with means for releasably supporting the blocks in its ends, a fuse cartridge shell, electrically-conductive bushings fitting within and closing the ends of the shell, one of the bushings being removable, fuse links in the shell, flexible conductor leaves connecting the links to the bushings, and means for releasably connecting the bushings to the terminal blocks.

2. Electrical fuse structure comprising a cartridge shell, electrically-conductive bushings fitting within and closing the ends of the shell, to retain filling material therein, fuse links in the shell, flexible conductor leaves connecting the links to the bushings, and threaded extensions on the bushings for effecting electrical and mechanical connections between the outer ends of the bushings and electrical conductors.

3. Electrical fuse structure comprising a cartridge shell, electrically-conductive bushings fitting within and closing the ends of the shell, to retain filling material therein, fuse links in the shell, flexible conductor leaves connecting the links to the bushings, and threaded extensions on the bushings for effecting electrical and mechanical connection between the outer ends of the bushings and electrical conductors, the bushings having vent holes for the escape of gases from the shell.

4. Electrical fuse structure comprising a cartridge shell, electrically-conductive bushings fitting within and closing the ends of the shell, a fuse link in the shell connected at one end to one of the bushings, an extensible conductor leaf connecting the other end of the link to the other bushing, and means for effecting electrical and mechanical connection between the outer ends of the bushings and electrical conductors, the said connection comprising threaded extensions on the bushings.

5. Electrical fuse structure comprising a cartridge shell, electrically-conductive bushings

closing the ends of the shell, a fuse link in the shell connected at one end to one of the bushings, an extensible and flexible conductor leaf connecting the other end of the link to the other bushing, and means for effecting electrical and mechanical connection between the outer ends of the bushings and electrical conductors, the conductor leaf being of such length that its associated bushing can be in withdrawn position relative to the shell while the other bushing is fixed in place.

6. Electrical fuse structure comprising a cartridge shell, electrically-conductive bushings closing the ends of the shell, to retain filling material therein, fuse links in the shell, flexible conductor leaves connecting the links to the bushings, and means for effecting electrical and mechanical connection between the outer ends of the bushings and electrical conductors, the said connection comprising threaded extensions on the bushings.

7. Electrical fuse structure comprising a cartridge shell, electrically-conductive bushings closing the ends of the shell, to retain filling material therein, fuse links in the shell, flexible conductor leaves connecting the links to the bushings, and means for effecting electrical and mechanical connection between the outer ends of the bushings and electrical conductors, one set of conductor leaves being of such length that their associated bushing can be in withdrawn position relative to the shell while the other bushing is fixed in place.

8. Electrical fuse structure comprising a cartridge shell, electrically-conductive bushings closing the ends of the shell, a fuse link in the shell connected at one end to one of the bushings, a flexible conductor leaf connecting the other end of the link to the other bushing, means for effecting electrical and mechanical connection between the outer ends of the bushings and electrical conductors, the said connection comprising threaded extensions of the bushings, and there being vent holes through the bushings and their threaded extensions, for the escape of gases from the shell, and closures for the inner ends of the holes, rupturable by gas explosions.
